US0D1040339S

(12) United States Design Patent (10) Patent No.: US D1,040,339 S
(45) Date of Patent: * Aug. 27, 2024

(54) DISPOSABLE DIAPER

(71) Applicant: Daio Paper Corporation, Shikokuchuo (JP)

(72) Inventors: Mizuho Osame, Shikokuchuo (JP); Aya Kusano, Shikokuchuo (JP)

(73) Assignee: Daio Paper Corporation, Shikokuchuo (JP)

() Term: 15 Years

(21) Appl. No.: 29/816,577

(22) Filed: Nov. 23, 2021

(30) Foreign Application Priority Data

May 25, 2021 (JP) 2021-010967

(51) LOC (14) Cl. 02-01

(52) U.S. Cl.

USPC D24/126

(58) Field of Classification Search

USPC D24/124, 125, 126, 189, 190, 191, 192

CPC A61F 13/15; A61F 13/64; A61F 13/5611;

A61F 13/4704

See application file for complete search history.

(57) CLAIM

The ornamental design for a disposable diaper, as shown and described.

DESCRIPTION

FIG. 1 is an isometric view of a disposable diaper, showing our design;

FIG. 2 is a front view thereof;

FIG. 3 is a rear view thereof;

FIG. 4 is a left side view thereof;

FIG. 5 is a right side view thereof;

FIG. 6 is a top view thereof; and,

FIG. 7 is a bottom view thereof.

The broken line showing in the Figures shows portions of the disposable diaper and forms no part of the claimed design.

1 Claim, 5 Drawing Sheets
